REFRIGERATED CASE

Malcolm D. MacMaster, Yardley, Pa., assignor to
 C. V. Hill & Company, Inc., a corporation of
 New Jersey

Application March 23, 1939, Serial No. 263,641

5 Claims. (Cl. 62—103)

My invention relates to refrigerated cases or other constructions having one or more doors providing access to a refrigerated space and particularly to constructions which serve to prevent moisture condensing upon elements adjacent the door from falling downward onto articles within the case.

In refrigerated cases and particularly cases of the display type one or more cooling coils are usually located in the upper portion of the case, so that warm air passing upward in the case will be cooled and circulated downward over the articles to be preserved. Baffle members are often located adjacent the coils to direct the flow of air within the case and to shield the coil from view. The doors provided at the rear of the case to permit access to the refrigerated space usually extend upward to a point adjacent the cooling coil with the result that when opened warm moist air comes into contact with the cold upper portion of the door frame and the baffle members or other elements located adjacent the cooling coil and the air is so chilled that it deposits moisture on the cold elements. Thereafter the moisture collects in drops along the lower edges of the door frame and on the baffles or other elements and either drips off or is shaken off on closing the door or when the case is otherwise jarred. This is particularly objectionable when the case is so formed that the rear doors are inclined or extend forward over articles within the case since the drops of water falling onto the articles may injure or contaminate them and render them unfit for sale or use.

In accordance with my invention these objections to constructions of the prior art are overcome by providing means which serve to conduct moisture collecting upon elements adjacent the cooling coils and door away from the elements and to a drip pan located beneath the cooling coil or to any other suitable receiving means. Preferably the means employed also serves as a baffle and is positioned with an upper portion beneath a portion of the door frame and a lower portion above the drip pan so as to conduct water falling upon or flowing over the baffle to the drip pan.

One of the objects of my invention is to eliminate the falling of drops of moisture from elements located near a cooling coil and adjacent a door in a refrigerated case onto objects being preserved and located beneath said elements.

Another object of my invention is to provide a display case having a cooling coil with a drip

pan beneath the same with a baffle for conducting liquids to said drip pan.

A further object of my invention is to provide a display case having doors to permit access thereto with means located beneath the upper edge of the door frame for collecting moisture condensing thereon on opening of the door.

These and other objects and features of my invention will appear from the following description thereof in which reference is made to the figures of the accompanying drawing which illustrates a preferred embodiment thereof as applied to a refrigerated display case.

In the drawing:

Fig. 1 is a vertical sectional view of a refrigerated display case embodying my invention, and

Fig. 2 is a perspective of a portion of a display case embodying the construction illustrated in Fig. 1.

In the construction illustrated a refrigerated display case is provided with cooling coils 2 having fins 4 and located near the top 6 of the case in position to cool warm air circulating over the same and cause it to flow downwardly through the case. Sliding doors 8 and 10 are provided for permitting access to the refrigerated space within the case and are movable longitudinally of an upper frame member 14 provided with guide rails 16 and 18. This construction is preferably of the type described and claimed in the copending application of Cyrus F. Hoffman, Serial No. 180,567, filed December 18, 1937. The portion 14 of the frame is inclined at a steep angle and may be substantially vertical and for this reason any moisture collecting upon the frame tends to flow downward toward the lower extremity 20 of the frame.

Beneath the cooling coils 2 and fins 4 are located drip pans 22 which preferably are of the type shown and described in my copending application Serial No. 263,634, filed March 23, 1939, and are inclined lengthwise of the case to conduct liquid falling from the fins during the "off-cycle" of operation to the ends of the case where it may be discharged in any suitable manner. A baffle number 24 is located near the front of the case and spaced from the fins 4 and drip pans 22 so as to cause warm air to flow upward outside the baffle into contact with the coils and to allow cool air to flow downward over the adjacent edge of the front drip pan 22 into the lower portion of the case. A baffle member 26 is located in the rear of the cooling coil and is positioned with the upper portion thereof extending beneath the lower extremity 20 of the

frame portion 14 whereas the lower edge of the baffle 26 extends over the edge of the rear drip pan 22 to discharge any liquid flowing downward over the same into the drip pan. The baffle 26 is formed with openings 28 therethrough to allow warm air flowing upward adjacent the doors to pass through the baffle to the cooling coils 2 and over the fins 4. The lower extremity of the baffle is also provided with a downwardly turned lip 30 which serves to prevent drops flowing down the inner surface of the baffle from swinging outward over the edge of the drip pan under the action of the surface tension which causes the drops to tend to adhere to the edge 15 of the baffle.

With this construction the dripping of liquid from the lower extremity of the frame is rendered unobjectionable since the liquid falls upon the baffle member 26 and is conducted thereby to the 20 drip pan so as to be discharged from the case. At the same time any moisture collecting upon the outer surface of the baffle 26 will flow downward upon this surface adhering to the baffle until it passes into the drip pan 22.

25 It will be noted that the baffle 24 at the front of the case does not extend over the drip pan as does the rear baffle 26. However this is unnecessary in most cases since the moisture content of the air within the case is generally so 30 low that the difficulties presented by "sweating" do not occur at the front of the case. On the other hand the depositing of moisture from warm air which enters the case at the rear thereof on opening the doors is much more serious and 35 difficult to overcome, particularly in warm moist climates. The construction described above and shown in the drawing overcome these objections and eliminate all danger of injuring or spoiling articles within the case by the dripping of moisture 40 thereon.

While I have shown and described a typical embodiment of my invention it will be apparent that numerous changes and modifications may be made in the form and arrangement of the 45 various elements of the combination and therefore it should be understood that the construction herein described and shown in the drawing are intended to be illustrative of my invention and are not intended to limit the scope thereof.

50 I claim:

1. In a refrigerated display case having a cooling coil located in the upper portion thereof, the combination of a door permitting access to the space within the case and a frame engageable by 55 said door, the upper portion of said frame being located adjacent said cooling coil and a baffle located adjacent said coil and beneath the edge of said portion of said frame in position to re-

ceive moisture dripping from said upper portion of said frame.

2. In a refrigerated display case having a cooling coil located in the upper portion thereof, the combination of a door permitting access to the space within the case and a frame engageable by said door, the upper portion of said frame being located adjacent said cooling coil and a baffle located adjacent said coil and beneath the edge of said portion of said frame in position to receive 10 moisture dripping from said upper portion of said frame, said baffle being spaced from said frame and provided with openings therethrough to permit ready circulation of air about and through the same to said cooling coil. 15

3. In a refrigerated case having a door providing access to the interior of said case, a frame for said door a cooling coil located near the top of said case and adjacent the upper portion of said frame, and a drip pan beneath the cooling coil 20 the combination of a baffle member located adjacent said coil and having the upper edge thereof beneath the upper edge of said frame and the lower edge thereof over said drip pan in position to direct condensate from said frame and 25 baffle to said drip pan.

4. In a refrigerated display case having a cooling coil located in the upper portion thereof, the combination of a door permitting access to the space within the case and a frame engageable by 30 said door, the upper portion of said door and frame being located adjacent said cooling coil, a drip pan beneath said coil, a baffle located on that side of the coil remote from said door and inclined outwardly at the bottom to permit air 35 to flow downward between the lower edges of said baffle and said drip pan, and a baffle located on that side of the coil adjacent the door and inclined inwardly over said drip pan to conduct liquid to said drip pan. 40

5. In a refrigerated display case having a cooling coil located in the upper portion thereof, the combination of door permitting access to the space within the case and a frame engageable by said door, the upper portion of said door and frame being located adjacent said cooling coil, a drip pan beneath said coil, a baffle located on that side of the coil remote from said door and inclined outwardly at the bottom to permit air 50 to flow downward between the lower edge of said baffle and said drip pan, and a baffle located on that side of the coil adjacent the door and positioned with the upper edge thereof beneath said frame, the lower portion of the baffle being inclined inwardly over said drip pan to conduct liquid to said drip pan. 55
